UNITED STATES PATENT OFFICE.

JOSEPH F. BUTLER, OF GORDON, TEXAS, ASSIGNOR TO WILLIAM W. JOHNSON, OF GORDON, TEXAS.

GATE.

1,095,378.

Specification of Letters Patent.

Patented May 5, 1914.

Application filed May 28, 1913. Serial No. 770,516.

To all whom it may concern:

Be it known that I, JOSEPH F. BUTLER, a citizen of the United States of America, residing at Gordon, in the county of Palo 5 Pinto and State of Texas, have invented certain new and useful Improvements in Gates, of which the following is a specification.

This invention relates to gates and one of the principal objects of the invention is to 10 provide simple, reliable and efficient means for sliding a gate suspended upon rollers and mounted on a track.

Another object of the invention is to simplify the construction of closing the gate 15 which shall operate smoothly and which is not liable to get out of order.

Still another object of the invention is to provide a suspended sliding gate which can be either opened or closed from either side 20 of the gate by pulling upon an operating cord.

These and other objects may be attained by means of the construction illustrated in the accompanying drawings, in which:

25 Figure 1 is a front elevation of the gate made in accordance with my invention and shown in closed position; Fig. 2 is a vertical sectional view of the same; Fig. 3 is a plan view of the operating lever; and Fig. 4 is a 30 front elevation of the gate shown in its opened position.

In the accompanying drawings, 1 are the upright posts connected together by a cross beam 2 and 3 is the roadway, while the space 35 4 at the left of the roadway may be provided with ordinary fencing at one side of the upright posts 1. At a point centrally between the posts 1 are short gate posts 5 disposed upon opposite sides of the gate. Secured to 40 the cross beam 2 and suitably spaced therefrom is a supporting rail 6. This rail is oppositely inclined at its upper edge, the ends 7 and the center 8 of the rail being narrower than the intermediate portions 9, the purpose 45 being to slightly raise the gate as it is moved and permit it to drop into the two positions opened and closed.

The gate may be of any desired construction. As shown the two vertical side members 10 are preferably of metal and provided at their upper ends with bent over portions 11 and journaled in said bent over portions are grooved rollers 12 adapted to run on the track 6 and to suspend the gate from said 50 track. Cross bars 13 and 14 connect the two

vertical members 10 and suitable braces 15 extend from the members 10 to the lower cross bar 14. Secured to the cross bar 14 is the lower member or bottom 16 of the gate, this bottom being of sufficient weight to compel the gate to drop by gravity when operated. Vertical guide bars 17 suitably spaced apart are secured centrally to the cross bars 13 and 14. 60

The operating lever comprises two diverging arms 18 having outwardly extending trunnions 19. As shown, this operating lever is composed of a metal rod of suitable gage bent at the point 20 to form the two members 18 and the trunnions 19. Mounted 70 centrally at the point 20 between the members 18 are spaced disks 21. The trunnions 19 are pivoted in suitable eye bolts 22 secured to the spaced posts 5. The point 20 of the lever is disposed between the two guide 75 bars 17 and the disks 21 are disposed upon opposite sides of said guide bars. Pivoted 80 connected to each of the members 18 of the lever is a T-shaped lever 23, said levers being each pivoted at 24 and provided with oppositely extending arms 25 said arms 25 each having a right angularly projecting finger 26 disposed upon opposite sides of the member 18. Pivoted at 27 to each member 18 is a trigger 28 having oppositely disposed hooks 85 29. Stop lugs 30 upon opposite sides of the trigger 28 serve to limit the pivotal movement of said trigger. 90

Connected to each lever 23 is an operating wire or cord 31 which is passed over a double roller 32 journaled in a bar 33 extending at right angles to the cross beam 2. Connected to each of the wires or cords 31 is a branch wire or cord 34 which extends over the roller 32 and around a pulley 35. At the 95 depending end of the cord is a hand hold 36. The cord or wire 31 extends over the pulleys 37 and 38 and is provided at the depending end with a hand hold 39.

The operation of my invention may be 100 briefly described as follows: When the gate is closed, as shown in Fig. 1 and a pull is exerted downward on either of the hand holds 36 or 39, the lever 18 is lifted owing to the fact that one of the fingers 26 on the lever 23 is engaged with one of the hooks 105 29 of the trigger while the other finger 26 extends across over the member 18. When the lever 18 is lifted a certain distance with the point 20 between the bars 17, the cord 110

31 will assume a position at the right hand side of the pivot 24 of the lever 23. The point 20 describes nearly a semi-circular movement and the gate is moved on the rail 6 from its closed position to the opened position shown in Fig. 4 at which time the lever 23 has shifted its position to engage the opposite hook 29 with its opposite finger 26 so that another pull upon either of the hand holds 36 or 39 will shift the gate to the original position. Thus it will be seen that the gate may be opened or closed from either side by pulling on either of the hand holds 36 or 39. In this embodiment of my invention I have shown only one operating lever 23 but should it be desired at any time, it is to be understood that I may use the operating mechanism on both sides without in any way departing from the spirit and scope 22 of my invention as set forth in the appended claim.

From the foregoing it will be obvious that my invention is comparatively simple in

construction, is reliable in action, will work smoothly and can be manufactured at low 25 cost.

I claim:

A sliding gate provided with a track rail, a gate provided with rollers mounted on said track rail, vertical guide bars on said gate, an operating lever mounted between said guide bars, a trigger pivoted to said operating lever and provided with hooks, a T-shaped lever pivoted to said operating lever, said T-shaped lever provided with lugs for 35 engaging the hooks on said trigger and an operating cord connected to said T-shaped lever for shifting the position of the operating lever and operating the gate.

In testimony whereof I affix my signature 40 in presence of two witnesses.

JOSEPH F. BUTLER.

Washington, D. C."

Correction in Letters Patent No. 1,095,378.

It is hereby certified that Letters Patent No. 1,095,378, granted May 5, 1914, upon the application of Joseph F. Butler, of Gordon, Texas, for an improvement in "Gates," were erroneously issued to William W. Johnson, as assignee of the entire interest in said invention, whereas said Letters Patent should have been issued to *the inventor, said Butler and William W. Johnson, jointly*, said Johnson being assignee of *one-half interest only*, in said invention, as shown by the records of assignments in this office, and the said Letters Patent should be read with this correction therein that the same may conform to the record of the case in the Patent Office.

Signed and sealed this 9th day of June, A. D., 1914.

[SEAL.]

J. T. NEWTON,

Acting Commissioner of Patents.
